Wilmington, Del., a corporation of Delaware

Application January 15, 1936, Serial No. 59,230

9 Claims. (Cl. 242—18)

This invention relates to the production of artificial thread and more particularly it relates to the production of artificial thread composed of organic cellulose derivatives such as cellulose esters and ethers which have a smooth, regular external surface.

In the dry spinning of cellulose derivative thread, the spinning solution is extruded continuously from a spinneret, and the resulting threads or filaments are led through a closed chamber for a distance which permits the substantially complete evaporation of the solvent employed. The thread if desired may be subjected to treatment with a thread finishing composition and is then continuously fed to and wound up on a rotating bobbin.

It has been customary to collect the dried thread, or substantially dried thread, by winding the same by means of suitable thread traversing mechanism on a wooden bobbin which is rotated by peripheral contact with a surface drive roll, or winding the threads on pirns which are rotated on positive driven spindles and traversing the thread on said pirns by means of bells or caps, such as, in cap spinning processes.

In the winding of threads on wooden bobbins, suitable spindles are inserted longitudinally through the centers of the bobbins to serve as journal bearings, and the spindle ends or journals of the bobbins are placed in vertical stationary guide grooves to hold the bobbins so that they may rest on the surface drive rolls to be driven by the latter. These bobbins are freely movable in a vertical direction, and as a consequence any slight irregularity or unevenness in the surface of the wound thread, or eccentricity in the surface of the bobbin or in the density of the wood of which the bobbins are usually constructed, creates an unbalanced condition in the revolution of the spindle in the vertical guide grooves, with the result that the spindle periodically bounces or jumps upward due to the said irregularities or eccentricities. It has furthermore been found that any irregularities in the bobbins or in the thread wound thereon will often cause a climbing of the bobbin due to pressure on the side walls of the vertical guide grooves by means of the spindle, and thereby cause a jumping or bouncing of the bobbin relative to the drive roll. Obviously this bouncing of the bobbin is very objectionable and attempts have been made in the past to eliminate the same.

It has been found that in the winding of organic cellulose derivative threads, the excessive

bouncing of the spindle coupled with the difficulty of maintaining spindle lengths and guide groove spacing in exact alignment, together with the increase in weight of the thread built up on the bobbin, has restricted the weight of yarn cheeses. In general, a $\frac{1}{2}$ or $\frac{3}{4}$ pound package of wound artificial thread is the upper limit at which a well formed package, free from bulging ends, overthrown threads and an excessive number of loops can be secured.

The prior art generally teaches that in the winding of cotton, woollen or other threads prepared from discontinuous filaments or from filaments having an uneven external surface, the package may best be produced by increasing the pressure between the bobbin and the surface drive roll to secure a smooth evenly wound package of comparatively large size. It has long been desired to produce a comparatively large, smooth evenly wound package containing threads composed of organic cellulose derivatives by winding the artificial thread directly from the dry spinning apparatus. However, artificial threads produced from organic cellulose derivatives comprise continuous filaments in substantially parallel alignment, which filaments are very even, smooth and slick on the external surface thereof, and consequently it has heretofore been found impossible to wind such thread directly from the dry spinning operation into large packages without producing bulging ends and overthrown threads. In prior attempts to follow the teaching of the art relating to winding of thread composed of discontinuous filaments by increasing the tension between the surface drive roll and the bobbin as the thread layers build up on the package, it has always been found that as soon as a sizable package is formed the inner thread layers will be pushed out from the ends of the package. Such a package is very undesirable for further processing due to entanglements of the thread layers at the bulged ends thereof.

It has now been found that a large, smooth evenly wound package free from bulging ends and overthrown threads and containing over two pounds of organic cellulose derivative thread can be produced by winding the artificial thread directly from the dry spinning apparatus.

It is therefore an object of this invention to produce smooth, evenly wound packages containing over two pounds of organic cellulose derivative thread directly from the spinning operation.

It is a further object of this invention to produce smooth, evenly wound packages containing

over two pounds of organic cellulose derivative thread directly from the spinning operation and without material bouncing or jumping of the package during the winding thereof.

5 It is a still further object of this invention to produce smooth, evenly wound packages containing over two pounds of organic cellulose derivative thread directly from the spinning operation by driving the bobbin on which the package is 10 wound with a surface drive roll without increasing the pressure between the bobbin and the surface drive roll as the thread builds up on the bobbin.

Other objects of the invention, including apparatus for carrying out the above named objects, will appear hereinafter.

The objects of the invention may be accomplished in general, by the winding of organic cellulose derivative thread on a removable bobbin 20 rotatably positioned on a pivoted swinging arm, which swinging arm rests the bobbin on a surface drive roll for rotation thereby, and is provided with means for applying a lifting action to the arm at least sufficient to compensate for the 25 increasing weight of the artificial thread as it builds up on the thread bobbin.

The details of the invention will be more readily apparent by reference to the following detailed description taken in connection with the 30 accompanying drawings illustrating certain specific modifications of the invention.

In the drawings:

Figure 1 is a side elevational view showing a winding apparatus suitable for carrying out the 35 production of thread packages in accordance with the present invention.

Figure 2 is a front elevational view of the apparatus shown in Figure 1.

Figure 3 is a side elevational view of a thread 40 winding mechanism illustrating a modified form of counterbalancing means for compensating for the weight of the thread as it builds up on the surface driven bobbin.

Referring to the drawings, reference numeral 45 11 designates generally a portion of a spinning cell of a dry spinning apparatus; the thread 14 issuing therefrom passes over guide rolls 12 and 16. The thread is then passed over a finishing roll 18 which may apply a finishing composition 50 to the thread. This may be achieved, for example, by rotating roll 18 within a container 20 in which a thread treating composition is placed. The thread then passes over guide roll 22 and feed rolls 24 and 26, and thence to thread guide 55 28 which is pivotally mounted on the reciprocating thread traversing bar 32 by means of rod 30. The thread layers 34 are built up on bobbin sleeve 36 which is removably positioned on freely 60 rotatable roller 38. The roller 38 is preferably mounted on pivot pin 39 by the interposition of ball bearings so as to permit exceptionally free and smooth rotation of roller 38. The bobbin sleeve 36 may be formed of any desirable material such as, for example, molded resinous materials which are capable of being readily balanced 65 dynamically with relation to the surface drive roller so that the said bobbin will operate smoothly and without bouncing. The roller 38 is preferably provided with means for holding the 70 removable bobbin sleeve 36 in a given position thereon so that the traversing thread guide 28 will always wind the layers of the thread on the bobbin sleeve 36 in a given predetermined position. The roller 38 and the bobbin sleeve 36, 75 which is securely mounted on said roller but is

removable therefrom, are driven by means of the surface drive roller 40 which is preferably driven at a constant rate of speed. The surface drive roller 40 may be driven in any desired manner by means of shaft 41. The pivot pin 39 is mounted on a swing arm 42, which in turn is pivotally mounted at 44 to a suitable supporting base. The swing arm 42 is provided with an integral arm 46 and is provided at the end of said arm 46 with a roller 48 which is freely rotatable on pivot pin 50 50. As the thread builds up on bobbin 36 the swing arm 42 will turn to the left hand position, as indicated by dotted lines in Figure 1, whereby the lever 46 and roller 48 will be rotated upwardly. A rotatable bell crank lever 52 is pivoted at 56 in such a position that a pressure shoe 54 mounted thereon will be directed against roller 48 whereby to lift the same together with lever 46 and swing arm 42 and thereby compensate for the increased weight of the bobbin 20 36 and thread cake 34 resting on the surface drive roller 40. The pressure shoe 54 is directed against the roller 48 by means of spring 58 which is mounted between arm 60 of lever 52 and fixed lug 62. The external surface of the pressure shoe 54 is preferably formed in the shape of an involute curve, or similar curve of increasing radius, so that as the pressure shoe 54 is rotated about pivot 56 by means of spring 58, the pressure directed against the roller 48 will be increased substantially in the same degree as the pressure increases due to the increased weight of the thread on the bobbin 36. The spring 58 may be made adjustable by mounting the same in an opening through fixed lug 62 and providing the 35 projecting end of the spring with a threaded portion 64 and a nut 66 as is clearly shown in Figure 1. By adjusting the spring to vary the tension thereon it is therefore possible to vary the pressure directed by shoe 54 against roller 48. The swing arm 42 may if desired be provided with an extension handle 35 whereby the bobbin sleeve may be lifted manually out of contact with the surface drive roll 40.

Referring to Figure 3 of the drawings, the 45 swing arm 70 is pivotally connected to a supporting base at 72, and is adapted to rest the bobbin sleeve 36 or thread layers 34 against the surface drive wheel 40 in the same manner as above defined with reference to Figures 1 and 2. The swing arm 70 is provided with an extension 50 75 in the opposite direction from the pivot 72. The extension 75 has a slot 74 formed therein, in which is adapted to be mounted a roller 76 which roller is freely rotatable about pivot 78 which in turn is fixedly mounted on bell crank lever 80. The bell crank lever 80 is pivoted at 82 to a supporting base and is provided with an oppositely extending arm 84 on which is positioned a weight 86. The weight 86 is mounted on the 55 arm 84 in any desired manner and is preferably provided with means to permit it to be adjusted along the length of arm 84 whereby to vary the lifting action on swing arm 70. The weight 86 will tend to push arm 84 of the bell crank lever 60 65 downwardly and thereby rotate, in an upward direction, the roller 76 which roller is positioned within slot 74 and therefore will tend to rotate swing arm 70 in a direction away from the surface drive roll 40.

In operation the thread, issuing continuously from the spinning cell is led over the guides and finishing rollers and fed to the reciprocating thread guide 28 and wound onto the rotating bobbin 36. It has been found particularly de- 75

sirable that the thread guide is of the mechanically reciprocating type. The grooved drum type traverse guide has been found to be inferior when used in combination with the above-described apparatus. As the thread builds up on bobbin 36 the swing arm 70 will be lifted with reference to drive roll 40, and the gradual increase in the weight of the yarn on the bobbin 36 and the consequent pressure increase between the bobbin 36 and the surface drive roll 40 will be compensated by a steadily increasing lifting force exerted by the pressure shoe 54 on roller 48 and arm 46 which is integral with swing arm 42. Although the force exerted by the tension spring 58 decreases slightly with the increased size of the package, nevertheless because of the involutely curved shape of the pressure shoe the lifting force applied to roller 48 and arm 46 is progressively increased by reason of the pressure shoe being gradually more effectively applied.

The outstanding advantage of this invention comprises the winding of a thread composed of an organic cellulose derivative having continuous filaments from a spinning cell with the formation of a uniformly wound package of unusually large size. It has long been desired to obtain such large packages directly from the spinning operation with cellulose derivative thread but has been found to be impossible heretofore due to the peculiarities of this particular type of thread. The package produced in the course of this invention is characterized from those formed heretofore, not only in its large size, but also in its being of a substantially uniform hardness throughout, and its being relatively free from bulged out ends and overthrown threads. In consequence of the production of the large size package, it is not necessary to stop the bobbin so frequently as is necessary in the prior art processes, and subsequent twisting or throwing operations involve considerably less labor and attention than in prior art processes. The quality of the yarn is also very materially improved by reason of the fact that less degradation results from the decreased amount of handling, the uniform pressure of winding, and the freedom from bouncing bobbins and vibrating spindles even at high winding speed. The yarn wound on the packages in accordance with the present invention contains a very much smaller number of knots per given yardage of thread due to the use of the large package, and in consequence of even pressure in winding whereby a smaller number of breaks occur in the thread. The elimination of many knots is obviously a great advantage in subsequent weaving and knitting operations in which the knots seriously interfere with the needles and frequently cause stoppage and expensive delays in the textile manufacturing operation.

Obviously many modifications and changes may be made in the above description without departing from the nature and spirit of the invention, and it is therefore to be understood that the invention is not to be limited hereto except as set forth in the appended claims.

We claim:

We claim:

1. In a thread winding apparatus, a positively driven surface drive roller, a bobbin positioned to rest by gravity on said roller, means connected to said bobbin whereby to lift the same, means positioned on said apparatus to co-act with said first-named means to exert a lifting force on said bobbin, said two above-named means so constructed and arranged that a constant force applied to said second-named means will progress-

sively exert an increasing lifting action on said bobbin as the thread builds up on the latter, and means for actuating said second-named means.

2. In a thread winding apparatus, a positively driven surface drive roller, a bobbin positioned to rest by gravity on said roller, means connected to said bobbin whereby to lift the same, means positioned on said apparatus to co-act with said first-named means to exert a lifting force on said bobbin, said two above-named means so constructed and arranged that a constant force applied to said second-named means will progressively exert an increasing lifting action on said bobbin as the thread builds up on the latter, and spring means for actuating said second-named means. 15

3. In a thread winding apparatus, a positively driven surface drive roller, a bobbin positioned to rest by gravity on said roller, means connected to said bobbin whereby to lift the same, means positioned on said apparatus to co-act with said first-named means to exert a lifting force on said bobbin, said two above-named means so constructed and arranged that a constant force applied to said second-named means will progressively exert an increasing lifting action on said bobbin as the thread builds up on the latter, and weight means for actuating said second-named means. 20 25

4. In a thread winding apparatus, a positively driven surface drive roller, a bobbin positioned to rest by gravity on said roller, means connected to said bobbin whereby to lift the same, leverage means positioned on said apparatus to co-act with said first-named means to exert a lifting force on said bobbin, said two above-named means so constructed and arranged that a constant force applied to said second-named means will progressively exert an increasing lifting action on said bobbin as the thread builds up on the latter, and means for actuating said second named means.

5. In a thread winding apparatus, a positively driven surface drive roller, a bobbin positioned to rest by gravity on said roller, means connected to said bobbin whereby to lift the same, a rotatable member positioned on said apparatus to contact with said means to exert a lifting force on said bobbin, said means and member so constructed and arranged that a constant force applied to said member will progressively exert an increasing lifting action on said bobbin as the thread builds up on the latter, and means for actuating said member.

6. In a thread winding apparatus, a positively driven surface drive roller, a pivotedly mounted swing arm, a bobbin freely rotatably mounted on said swing arm, said swing arm positioned, relative to said roller, to permit said bobbin to rest on said roller by gravity, means connected to said swing arm whereby to lift the same, means positioned on said apparatus to co-act with said first-named means to exert a lifting force on said bobbin, said two above-named means so constructed and arranged that a constant force applied to said member will progressively exert an increasing lifting action on said swing arm as the thread builds up on the bobbin, and means for actuating said second-named means. 55 60 65

7. In a thread winding apparatus, a positively driven surface drive roller, a bobbin positioned to rest by gravity on said roller, means connected to said bobbin whereby to lift the same, a rotatable member having a curved surface of increasing radius with respect to its axis, said 75

- member mounted on said apparatus with the said curved surface positioned to co-act with said means to exert a lifting force on said bobbin, said member and means so constructed and arranged that a constant force applied to said member will progressively exert an increasing lifting action on said bobbin as the thread builds up on the latter, and means for rotating said member.
8. In a thread winding apparatus, a positively driven surface drive roller, a bobbin positioned to rest by gravity on said roller, means connected to said bobbin whereby to lift the same, a rotatable member having an involute curved surface of increasing radius with respect to its axis, said member mounted on said apparatus with the said curved surface positioned to co-act with said means to exert a lifting force on said bobbin, said member and means so constructed and arranged that a constant force applied to said member will progressively exert an increasing
- lifting action on said bobbin as the thread builds up on the latter, and means for rotating said member.
9. In a thread winding apparatus, a positively driven surface drive roller, a bobbin, said bobbin mounted to press against said roller, means connected to said bobbin whereby to move the same away from said roller, means positioned on said apparatus to co-act with said first-named means to exert a moving force on said bobbin away from said roller whereby to reduce the pressure between bobbin and roller, said two above-named means so constructed and arranged that a constant force applied to said second-named means will progressively exert an increasing moving force on said bobbin away from said roller as the thread builds up on said bobbin, and means for actuating said second-named means.

HARRY S. TOOLE. 20
